Inventor:

Max Buck,

by Oscar Middleton Donaldson, Atty's.

UNITED STATES PATENT OFFICE.

MAX BUCH, OF DETROIT, MICHIGAN, ASSIGNOR TO HENRY E. EDWARDS, OF JACKSON, MICHIGAN.

TOP FOR VEHICLES AND THE LIKE.

1,287,212.

Specification of Letters Patent. Patented Dec. 10, 1918.

Application filed December 22, 1917. Serial No. 208,477.

To all whom it may concern:

Be it known that I, MAX BUCH, a subject of the Emperor of Germany, and resident of Detroit, Michigan, have invented certain new and useful Improvements in Tops for Vehicles and the like, of which the following is a specification.

My present invention relates to improvements in folding tops for motor vehicles and the like, and aims to provide an extremely simple and economical form of top, which shall be self-supporting during its folding and projecting movement, thus enabling it to be operated by a single individual, and 15 the folds of the covering material to be properly arranged.

The invention further aims to provide a construction in which the bow arms or parts will be prevented from dropping down below the body line in the folding of the top, thus avoiding the liability of striking the doors, should the same be left open.

With these and other objects in view the invention includes the novel features of construction and arrangement and combination of parts hereinafter described, my said invention being defined by the appended claim.

An embodiment of my invention is illustrated in the accompanying drawings, in which,

Figure 1 is a side elevation of a top showing the same in full lines in extended position, and in dotted lines in partially folded condition.

Fig. 2 is a detail, and

Fig. 3 is a view of a modification.

In these drawings the top being shown in side elevation only the standard and bow arms or links on one side appear, but it will be understood that they are duplicated on the other side, only one side being shown for convenience. Similarly in the following description and claim where reference is made to the members on one side it will be understood that this is for convenience only, and that the members on the opposite side are inferentially included.

Referring by reference characters to this drawing, the numeral 1 designates the body of the conveyance for which the top is adapted, and which is intended to be representative of any type of vehicle or motor boat needing such a protective covering.

The top covering is indicated at 2, supported by the folding frame hereinafter described. This comprises a main standard 3, which in the present drawing I have shown pivoted at 3^a to the rear bow arm 4, which latter is pivoted to the vehicle body at 4^a. It will be understood, however, that this manner of supporting the main standard 3 and the rear bow arm 4 from the vehicle may be varied, as instead the main standard might be pivoted to the vehicle body and the rear bow arm pivoted to the main standard, as is common in the art. 5 designates the outrigger bow arm, which has its rear end pivotally connected to the front end of a link or member 6, preferably by a pivot joint, as indicated at 5^a. The cover material is supported at a suitable distance back from the outrigger bow by an auxiliary front bow 7, which is pivotally connected at 7^a to the outrigger bow arm 5, and which inclines rearwardly upward therefrom as shown. This auxiliary front bow is, in the extended position of the top, held braced in proper position by a link 8, which has its forward end pivotally connected to the auxiliary front bow at 8^a, and its rear end pivotally connected to the link or member 6 at 8^b.

A link or member 9 is pivotally connected at its front end to the link 8, as indicated at 9^a and to the main standard 3, by the pivot joint, indicated at 9^b. This link 9 is continued in rear of the standard, as indicated at 9^c. This rearwardly extending part forms a bow arm for a rear auxiliary bow, it being understood that the part 9^c may be in the shape of an arm adapted to carry the ordinary wooden bow or may be formed integral with the bow, as desired. The part 9^c may be inclined upward at a greater angle relative to the covering, as shown in the drawings.

The standard 3, as shown, inclines forwardly from its pivot and when the joint 5^a is broken downwardly in folding the pull of the top covering upon the rearwardly extended bow arm 9^c serves to balance the front extension, and prevent it from dropping down, and enables it to be moved back from one side only into the position shown in dotted lines, where it will be supported, permitting the operator to properly ar-

range the covering material preparatory to the folding of the top completely back.

When the top is in its extended position, the link or member 8 rests upon the top of the joint 5^a, or an extension of the pivot pin thereof, and this enables me to use a plain pivot joint, which is more economical in manipulation. If desired, however, a lock pivot joint could be employed, in which 10 event contact of member 8 with the lock joint would not be absolutely necessary, though it might be desirable as relieving the lock joint of strain.

I sometimes prefer to provide between 15 two of said links a spring tending to project the top.

One arrangement of spring is shown at 10 in Fig. 1, and another arrangement at 10^a in Fig. 3, in which figure the outrigger

joint is shown as a lock joint, as indicated 20 at 5^a.

What I claim is:

In a folding top a supporting standard, an outrigger bow arm, a link pivotally connected to said outrigger bow arm and to 25 said standard, an auxiliary front bow arm pivoted to the outrigger bow arm and inclining rearwardly therefrom, a second link pivotally connected respectively to said auxiliary bow arm, and to said first named 30 link, and a third link pivotally connected respectively to said second named link, and to said main standard, said third link having a part extended to the rear of the main standard, and constituting an auxiliary rear 35 bow arm.

In testimony whereof, I affix my signature.

MAX BUCH.
